RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,315,959.

Specification of Letters Patent. Patented Sept. 16, 1919.

Application filed May 8, 1916. Serial No. 96,234.

To all whom it may concern:

Be it known that I, RUDOLF E. HELLMUND, a subject of the Emperor of Germany, and a resident of Pittsburgh, in the county of Allegheny and State of Pennsylvania, have invented a new and useful Improvement in Systems of Control, of which the following is a specification.

My invention relates to systems of control and especially to the regenerative control of direct-current electric railway motors and the like.

One of the objects of my invention is to provide a system of the above-indicated character which shall be relatively simple and inexpensive in construction and effective and reliable in operation and which shall embody certain novel and advantageous operating features, as hereinafter more fully set forth.

In a more specific aspect, it is an object of my invention to provide, in a regenerative control system of the class under consideration, means for inherently and automatically producing a negative compounding effect in the main momentum-driven machines, whereby an incipient increase of regenerated current is immediately counteracted by a corresponding decrease of main field-winding current, and, in addition, an auxiliary exciting generator for the main field windings which shall have a positive compounding characteristic and thus serve to aid the inherent regulating action just recited.

By the term "negative compounding characteristic" is meant an inherent tendency to decrease the main-field-winding current upon an incipient increase of main-armature current, and vice versa; while the expression "positive compounding characteristic" signifies that the field-winding and armature currents inherently tend to concurrently vary in the same direction, that is, the one increases when the other increases.

My invention may best be understood by reference to the accompanying drawing wherein Figure 1 is a diagrammatic view of a system of control embodying my invention; Fig. 2 is a similar view of a modification thereof; and Fig. 2A is a chart serving to set forth certain flux relations in the machine that is shown in Fig. 2.

Referring to the drawing, the system here shown comprises a plurality of supply-circuit conductors respectively marked "Trol-

ley" and "Ground"; a plurality of main dynamo-electric machines respectively having armatures A1 and A2 and field-magnet windings F1 and F2 of the series type; a plurality of main-circuit regulating resistors R1 and R2 that are associated with the respective main machines in a manner to be described; and an auxiliary motor-generator set or dynamotor that is adapted to be driven from the supply circuit and to excite the main field windings, as set forth more fully later.

The auxiliary motor generator set is shown as comprising a driving armature M and an exciting armature G that may be mechanically associated with the armature M in any suitable manner, as by a shaft s; a plurality of field-magnet windings MF and GF of the series type for the respective armatures M and G; and a shunt or supply-circuit-excited field-magnet winding GF1 for the armature G.

An auxiliary variable resistor AR1 is connected in series relation with the supply-circuit-excited field-magnet winding GF1 and is adapted to be varied in active circuit value by a plurality of switches 1 and 2; and a second auxiliary resistor AR2 is adapted to be connected in shunt relation to the series field winding GF by the closure of switch 3, and the value of the resistor may be varied by the manipulation of switches 4 and 5.

Inasmuch as my present invention pertains only indirectly to the type of regenerative control system that is employed, I have not deemed it necessary to show and describe means for initially connecting the various machines as illustrated, or means for inaugurating regenerative operation. The main system, here shown for illustrative purposes only, is fully set forth and claimed in my co-pending application, Serial No. 44,443, filed August 9, 1915.

Assuming that regenerative operation has been started in any suitable manner and that the various circuit connections are as illustrated in the drawing, such connections may be traced as follows: one main circuit is established from the trolley through junction-point 10, conductor 11, main armature A1, conductor 12, junction-point 13, main-circuit resistor R1, switching device 14, which is here conventionally shown as an arrow-head, junction-point 15 and conduc-

tors 16 and 17 to the negative conductor Ground. A second similar main circuit is established from the junction-point 10 through conductors 18 and 19, main armature A2, conductor 20, junction-point 21, main-circuit resistors R2, switching device 22, which corresponds to the switching device 14, and thence through junction-point 15 as just recited.

- 10 One terminal 23 of the auxiliary exciting generator G is connected through conductors 24 and 25 to the conductor 16 and junction-point 15, where the circuit divides, one branch including switching device 14, main-circuit resistor R1, junction-point 18, main field winding F1 and conductor 26 to a junction-point 27, and the other branch including switching device 22, main-circuit resistor R2, junction-point 21, main field winding F2 and junction-point 27, whence circuit is completed through conductor 28 to the other terminal 29 of the auxiliary exciting armature G.

An auxiliary circuit is completed from the conductor 18 through conductors 30 and 31, the driving armature winding M of the motor-generator set, series field winding MF, conductor 32, series field winding GF and conductor 25 to the negative conductor 17. The load current of the motor-generator set thus traverses both of the series field windings MF and GF, for purposes to be described.

A further auxiliary circuit is completed from the conductor 30 through conductor 33, auxiliary resistor AR1, field winding GF1, and thence through conductor 24 as previously described. Thus the field winding GF1 is connected, through the variable resistor AR1, across the supply circuit.

As indicated by the positive and negative signs and by the legend "Differential," the series field winding GF is adapted to increase the delivered voltage of the exciting armature G upon increased load conditions of the motor-generator set, whereas the supply-circuit-excited field winding GF1 exerts a negative or opposing action, or, in other words, is differentially related with respect to the series field winding GF, which, under normal conditions, predominates over the shunt field winding GF1. Such relation of parts causes the exciting armature G to have a positive self-compounding characteristic, that is to say, the effective flux delivered to the armature winding G is such that the voltage produced thereby varies in accordance with load conditions of the motor-generator set. This action is of advantage in aiding the negative compound characteristic of the main motors during the regenerative period, as set forth later.

It should be noted that, inasmuch as the driving armature M is provided with straight series excitation, the armature is

but slightly liable to "flash-over" troubles for the well-known reason that, in case of an interruption of supply-circuit voltage and a sudden resumption thereof such as occurs, for example, when the current-collecting member of the vehicle leaves the wire temporarily, the field flux of the driving motor of the motor-generator set is built up in a relatively rapid manner. Thus, the field flux is not unduly distorted by the initial restored armature-current flux and, consequently, "flash-over" conditions do not obtain.

Moreover, by reason of the differential relation of the field windings GF and GF1 of the exciting armature G, the sudden rise of regenerated voltage which tends to occur upon an interruption of supply-circuit voltage, and which rise if unchecked, would tend to produce abnormally high voltage between commutator bars of the various machines and probably "flash-over" troubles as a result, is prevented from reaching an undesirably high value by reason of the fact that any increase of the flux produced by the series field winding GF is counteracted or annulled by a correspondingly increased negative or differential action of the field winding GF1. The field windings may be so designed that, under the circumstances just mentioned, the counteracting effect of the supply-circuit-excited field-magnet winding GF1 will overcome the positive energizing action of the series field winding GF and thus cause a reduction of the main field-winding excitation, whereby the above-mentioned dangerous rise of voltage is effectively precluded.

Furthermore, the motor-generator set under consideration lends itself particularly well toward producing a damping effect upon voltage fluctuations of the supply circuit. Such damping effect is, in part, provided by the well-known choke-coil action of the shunt field winding GF1 which, as is customary, comprises a relatively large number of turns of fine wire, and partially by the buffer or damping action of the auxiliary resistor AR2 when connected in shunt relation to the series field winding GF. Still further damping effect may be obtained, if desired, by introducing dampers of the well-known gridiron type, for example, in the polar faces of the auxiliary exciting generator. The damping effect in question is desirable in some instances, by reason of the fact that it is then possible for over-voltage relay devices to effect the opening of main-circuit switches, in accordance with customary practice, because of the time element involved, before the above-mentioned rise of voltage exceeds a predetermined value for which the relays are set, thereby preventing injury to the various dynamo-electric machines.

Assuming that regenerative operation has been inaugurated, the operation of the above-described system may be set forth as follows: As indicated by the various arrows, 5 the main regenerated current traverses the main-circuit resistors R1 and R2 in the same direction as does the auxiliary exciting current that is supplied by the auxiliary armature G, whereas the currents in the allied 10 main armatures and field windings A1 and F1, for example, travel in opposite directions. As a result, an incipient increase of regenerated current produces a correspondingly augmented voltage drop in the corresponding 15 main-circuit resistor, whereby the exciting voltage available for delivery to the corresponding main field winding from the approximately constant-voltage armature winding G is accordingly decreased, and 20 thus the regenerated current in the corresponding main armature is reduced to the normal and desirable substantially constant value. The reverse action, of course, occurs upon an incipient decrease of regenerated 25 current in either main armature. Such action is more fully set forth in my above-identified co-pending application but it is believed that the foregoing description will be sufficient for the purposes of the present 30 specification.

However, under the above-mentioned conditions, a further inherent regulating action takes place, since, when an increased current traverse a main-contact resistor, the 35 general result corresponds to a virtual increase of circuit resistance, whereby a decreased current traverses the corresponding main field winding and the auxiliary exciting armature G. Consequently, the reduced 40 energy demand from the armature G causes a corresponding decrease of the current traversing the driving armature M and the series field windings MF and GF, whereby the voltage of the auxiliary armature G is 45 accordingly reduced by reason of the differential action of the field windings GF and GF1, or, in other words, because of the positive compounding characteristic of the armature G. It will be understood that, under 50 the converse condition of an incipient decrease of the regenerated current, the flux of the series field winding GF will be correspondingly augmented and thus induce an increased voltage in the auxiliary armature G. The action just described, of course, takes place in a relatively rapid manner and the positive compounding effect of the exciting generator thus tends to aid the inherent negative compounding effect of the 55 main machines to immediately and automatically counteract incipient changes of regenerated current and thus maintain a substantially constant flow of current to the supply circuit.

As pointed out in detail, in my above-

mentioned co-pending application, the switching devices 14 and 22 that are associated with the main-circuit resistors R1 and R2 may be varied, preferably in an automatic manner in accordance with the 70 value of regenerated current, as the speed of the momentum-driven machines decreases. However, in the present system, further or sole regulation may be obtained by suitably manipulating the switches 1 to 5, inclusive, to effect a gradual increase of the voltage of the auxiliary armature G as the vehicle speed decreases. The last-mentioned regulation involves the switching of relatively small currents, and the use of relatively small and inexpensive switches, as will be understood, and is advantageous in these respects.

Reference may now be had to Fig. 2, wherein the main-circuit connections are the 85 same as those described in connection with Fig. 1. In the present system, the exciting armature winding G is connected in series relation with a field-magnet winding GF2, which corresponds to the series field winding GF of Fig. 1, to excite the main field-winding circuits in a manner similar to that already set forth. The series field winding GF2 is provided with the shunting resistor AR2 for the same purpose as that explained 90 in connection with the previous system.

The driving motor of the motor-generator set that is shown in Fig. 2 comprises the armature winding M, and a stator frame or yoke SF which is provided with a plurality of oppositely-disposed, inwardly-extending main polar projections MP1 and MP2 and a plurality of auxiliary polar projections AP1 and AP2 that are disposed in quadrature relation to the main polar 100 projections. A series field winding MF is disposed upon the main polar projections, while a shunt field winding MF1 is wound around the auxiliary polar projections, as 105 set forth in detail later.

The circuit connections of the driving motor under consideration may be described as follows: The driving-motor main circuit is completed from the trolley through junction-point 10, conductors 11 and 40, junction-point 41, conductor 42, the portion of the series field winding MF that is disposed upon the main polar projection MP1, conductor 43, the remaining portion of the field winding MF that is wound around the 110 main polar projection MP2, conductor 44, brush 1, the armature winding M, brush 2 and conductors 45, 46 and 47 to the negative conductor Ground. A further auxiliary circuit is completed from the junction-point 41 through conductor 48, the portion of the shunt field winding MF1 that is wound around the auxiliary polar projection AP1, conductor 49, the remaining portion of the shunt field winding MF1 that 115 120 125 130

is disposed upon the auxiliary polar projection AP2 and conductor 50 to the negative conductor Ground.

As indicated by the letters *n* and *s*, the main polar projections MP1 and MP2 are respectively of positive and negative magnetic polarity, whereas the auxiliary polar projections AP1 and AP2 correspond in polarity to the main projections MP1 and 10 MP2, as designated by the characters *n'* and *s'*. The flux from both the main and the auxiliary north polar projections, therefore, threads the armature winding M in the same direction.

15 The machine just described is well adapted to inherently prevent "flash-over" conditions, by reason of the relative arrangement of main and auxiliary polar projections with respect to the brushes 1 and 2 20 of the motor armature winding M. As indicated by the solid arrows in Fig. 2A, the main polar projection MP1 and the auxiliary polar projection AP1, which are of north magnetic polarity, create fluxes which 25 travel from the stator frame SF through the polar projections to the armature M. The armature-reaction or cross-field flux, however, tends to oppose the flux that is emitted by the main polar projection MP1, in accordance with a familiar principle; but, by 30 reason of the peculiar location of the auxiliary polar projection AP1, such cross-field flux traverses that polar projection in the same direction as does the auxiliary polar 35 flux itself. The path of the cross-field flux in question is indicated by dotted lines in Fig. 2 and Fig. 2A.

The location of the main and auxiliary polar projections with respect to the brushes 40 1 and 2 may be specifically described as follows: Assuming the direction of rotation of the armature M to be as indicated by the curved arrow in Fig. 2, it will be noted that the auxiliary polar projections 45 AP1 and AP2 are disposed near the forward or toe portions of the brushes 2 and 1, respectively, whereas the main polar projections MP1 and MP2, being disposed intermediate the auxiliary polar projections, 50 of course, are respectively located near the rear or heel portions of the brushes 2 and 1, respectively.

Assuming a sudden resumption of supply-circuit voltage after a temporary interruption thereof, the flux that is produced by 55 restored armature current has tended to assume abnormal proportions in most machines of the prior art and has, consequently, effected an undue distortion of the 60 simultaneous field flux, which has usually taken a longer time to build up by reason of the higher inductance of the field-structure magnetic circuit. Graphically, the restored armature current flux that corresponds to the initial rush of current upon the

resumption of supply-circuit voltage, may be represented by the dot-and-dash curve X of Fig. 2A, whereby it will be seen that a relatively high flux value obtains adjacent to the motor commutator cylinder brush 1, for 70 example, and, consequently, under such conditions, abnormally high voltages between commutator segments and resultant "flash-over" conditions are liable to occur. On the other hand, the restored armature current flux within the zone of influence of the main polar projection MP1, for example, in machines of the prior art, has assumed a relatively low value by reason of the fact that the flux that is produced by 80 the main polar projection builds up at a comparatively rapid rate, inasmuch as the choke-coil action of the series winding is relatively small and, therefore, the armature current flux is prevented from reaching 85 dangerous values within the zone in question.

According to my present invention, however, by reason of the above-described path of the armature-reaction or cross-field flux, 90 the damping effect or choke-coil action of the auxiliary polar projection AP1 upon which the shunt-excited field winding MF1 is wound, is augmented to a material degree by the combined auxiliary polar flux 95 and cross-field flux which act cumulatively. In the main polar projection MP1, however, the rapidly increasing polar flux is partially neutralized by the effect of the cross-field flux under consideration and, consequently, the restored armature current flux attains a materially lower value than 100 has been the case heretofore, within the zone of influence of the auxiliary polar projection AP1, but a somewhat higher, although not undesirable, value within the 105 zone of influence of the main polar projection MP1, as indicated by the solid line curve Y. It will be understood that the contour of the curve Y will vary in accordance with the relative exciting fluxes of 110 the main and the auxiliary polar projections, although, in any case, the above-described dangerously high values of restored armature current flux are effectively prevented. 115

It will be observed that I have provided a regenerative system of control having a desirable negative compounding characteristic whereby a substantially constant regenerated current may be maintained, and the motor-generator set that is employed for exciting the main-machine field windings, has the one or the other of its armatures provided with a compound field winding 120 comprising a series field-magnet winding and a shunt field-magnet winding that are connected in circuit to perform predetermined mutual functions, while the remaining armature is provided with a series-con- 125 130

5 nected field winding. Both of the illus-
6 trated modifications are particularly adapt-
7 ed to prevent "flash-over" conditions in the
8 motor-generator set, for the reasons pre-
9 viously pointed out.

10 I do not wish to be restricted to the spe-
11 cific circuit connections or location and ar-
12 rangement of parts herein set forth, as var-
13 ious modifications thereof may be effected
14 without departing from the spirit and scope
15 of my invention. I desire, therefore, that
16 only such limitations shall be imposed as
17 are indicated in the appended claims.

18 I claim as my invention:

19 1. In a system of control, the combination
20 with a supply circuit, and a main dynamo-
21 electric machine having an armature and a
22 field winding, of an auxiliary motor-gener-
23 ator set having its armatures respectively
24 driven from the supply-circuit and connect-
25 ed to excite said field winding and having
one of said auxiliary armatures provided
with differentially-related field magnet
windings respectively energized from said
supply circuit and energized in accordance
with predetermined load conditions of said
set.

26 2. In a system of control, the combination
27 with a supply circuit, and a main dynamo-
28 electric machine having an armature and a
29 field winding, of an auxiliary motor-gener-
30 ator set having its armatures respectively
31 driven from the supply circuit and connect-
32 ed to excite said field winding, and hav-
33 ing said exciting armature provided with
34 differentially-related field-magnet windings
35 respectively energized from said supply cir-
36 cuit and energized in accordance with the
37 driving armature load of said set and also
38 having said driving armature provided with
39 a series-connected field-magnet winding.

40 3. In a system of control, the combination
41 with a supply circuit, and a main dynamo-
42 electric machine having an armature and a
43 field winding, of an auxiliary motor-gener-
44 ator set having its armatures respectively
45 driven from the supply circuit and connect-
46 ed to excite said field winding, and hav-
47 ing said auxiliary armatures provided with
48 field windings connected in series relation
49 with said driving armature, and means for
50 diverting current from one of said field
51 windings under predetermined conditions.

52 4. In a system of control, the combination
53 with a supply circuit, and a main dynamo-
54 electric machine having an armature and a
55 field winding, of an auxiliary motor-gener-
56 ator set comprising a pair of armatures
57 respectively driven from the supply circuit
58 and connected to excite said field winding,
59 field-magnet windings for the respective
60 auxiliary armatures connected in series rela-
61 tion with said driving armature, and a sup-
62 ply-circuit-excited field-magnet winding for
63 the exciting armature for producing a pre-

64 determined voltage-fluctuation damping ef-
65 fect, and further damping means comprising
66 a variable translating device connected
67 in shunt to the series field winding of the
68 exciting armature.

70

71 5. In a system of direct-current regenera-
72 tive control, the combination with a supply
73 circuit, and a momentum-driven main dy-
74 namo-electric machine having an armature
75 and a field winding, of an auxiliary motor-
76 generator set comprising a pair of arma-
77 tures respectively driven from the supply
78 circuit and connected to excite said field
79 winding, field-magnet windings for the re-
80 spective auxiliary armatures connected in
81 series relation with said driving armatures,
82 and a supply-circuit-excited field-magnet
83 winding for the exciting armature, and
84 means for regulating the regenerative op-
85 eration of the main machine, said means
86 comprising a variable resistor connected in
87 series relation with said supply-circuit-ex-
88 cited field winding and a second variable
89 resistor connected in shunt relation to the
90 series field winding of the exciting armature.

90

91 6. In a system of direct-current regenera-
92 tive control, the combination with a supply
93 circuit, and a momentum-driven main dy-
94 namo-electric machine having an armature
95 and a field winding, of a pair of mechani-
96 cally-connected auxiliary armatures respec-
97 tively driven from the supply circuit and
98 connected to excite said field winding, means
99 for varying the excitation of the exciting
100 armature in accordance with the current
101 traversing said armature, and means for
102 varying the main field-winding current op-
103 positely to the regenerated current.

100

104 7. In a system of direct-current regenera-
105 tive control, the combination with a supply
106 circuit, and a momentum-driven main dy-
107 namo-electric machine having an armature
108 and a field winding, of a pair of mechani-
109 cally-connected auxiliary armatures respec-
110 tively driven from the supply circuit and
111 connected to excite said field winding, a re-
112 sistor connected in series-circuit relation
113 with said main armature and in parallel-
114 circuit relation to said main field winding
115 and said exciting armature, and means for
116 varying the excitation of the exciting ar-
117 mature in accordance with the current trav-
118 ersing said armature.

116

119 8. In a system of direct-current regenera-
120 tive control, the combination with a supply
121 circuit, and a momentum-driven main dy-
122 namo-electric machine having an armature
123 and a field winding, of a pair of mechani-
124 cally-connected auxiliary armatures respec-
125 tively driven from the supply circuit and
126 connected to excite said field winding, a re-
127 sistor connected in series-circuit relation
128 with said main armature and in parallel-
129 circuit relation to said main field winding
130 and said exciting armature, field-magnet

130

winding for the respective auxiliary armatures connected in series relation with said driving armature, and a supply-circuit-excited field-magnet winding for the exciting armature differentially related with respect to the corresponding series field winding.

9. In a system of direct-current regenerative control, the combination with a supply circuit, and a momentum-driven main dynamo-electric machine having an armature and a field winding, of a pair of mechanically-connected auxiliary armatures respectively driven from the supply circuit and connected to excite said field winding, a resistor connected in series-circuit relation with said main armature and in parallel-circuit relation to said main field winding and said exciting armature, field-magnet winding for the respective auxiliary armatures connected in series relation with said driving armature, a supply-circuit-excited field-magnet winding for the exciting armature differentially related with respect to the corresponding series field winding, and means for regulating the regenerative operation of the main machine, said means comprising a variable resistor connected in series relation with said supply-circuit-excited field winding and a second variable resistor connected in shunt relation to the series field winding of the exciting armature.

10. In a system of control, the combination with a supply circuit, and a main dynamo-electric machine having an armature and a field winding, of an auxiliary motor-generator set having its armatures respectively driven from the supply circuit and connected to excite said field winding and having a series-related field winding for each auxiliary armature, and parallel-circuit connections for regulating the effect of the series field winding for said exciting armature.

11. In a system of control, the combination with a supply circuit, and a main dynamo-electric machine having an armature and a field winding, of an auxiliary motor-generator set having its armatures respectively driven from the supply circuit and connected to excite said field-winding, field-magnet windings for the respective auxiliary armatures connected in series relation with said driving armature, and a shunt-excited field-magnet winding for the exciting armature, whereby said exciting armature is associated with a field structure having a voltage-fluctuation damping effect and said driving armature is associated with a field structure having a non-damping effect.

12. In a system of control, the combination with a supply circuit, and a main dynamo-electric machine having an armature and a field winding, of an auxiliary motor-generator set having its armatures respectively driven from the supply circuit and connect-

ed to excite said field winding, a resistor and a field winding for each auxiliary armature connected in circuit with the motor of the motor-generator set, and means for varying said resistor to regulate the voltage of the field winding for said exciting armature.

13. In a system of control, the combination with a supply circuit, and a main dynamo-electric machine having an armature and a field winding, of a plurality of mechanically-connected armature windings respectively driven from the supply circuit and connected to excite said field winding, and a plurality of differentially-related field-magnet windings for one of said armature windings respectively energized from said supply circuit and energized in accordance with predetermined load conditions of the armature windings.

14. In a system of control, the combination with a supply circuit, and a main dynamo-electric machine having an armature and a field winding, of a plurality of mechanically-connected armature windings respectively driven from the supply circuit and connected to excite said field winding, a series-related field winding for each auxiliary armature winding, and parallel-circuit connections for regulating the effect of the series field winding for said exciting armature winding.

15. In a system of control, the combination with a supply circuit, and a main dynamo-electric machine having an armature and a field winding, of a plurality of mechanically-connected armature windings respectively driven from the supply circuit and connected to excite said field winding, a plurality of differentially-related field-magnet windings for said exciting armature winding respectively energized from said supply circuit and energized in accordance with the driving armature load, and a series-connected field-magnet winding for the driving armature.

16. In a system of control, the combination with a supply-circuit, and a main dynamo-electric machine having an armature and a field winding, of an auxiliary motor-generator set having its armatures respectively driven from the supply circuit and connected to excite said field winding, and having a field winding for the exciting armature adapted to decrease the voltage thereof upon an increase of supply-circuit voltage.

17. In a system of control, the combination with a supply circuit, and a main dynamo-electric machine having an armature and a field winding, of a plurality of mechanically-connected armature windings respectively driven from the supply circuit and connected to excite said field winding, a plurality of series field windings for said armature windings energized in accordance

with predetermined load conditions of the armature windings, and a shunt-excited field winding for one of the armature windings.

18. In a system of control, the combination with a supply circuit and a main dynamo-electric machine having an armature and a field winding, of an auxiliary armature connected to excite said field winding, and a plurality of differentially-related field magnet windings for said auxiliary armature respectively energized from said supply circuit and excited substantially in proportion to the load conditions of said auxiliary armature.
19. In a system of control, the combination with a supply circuit and a main dynamo-electric machine having an armature and a field winding, of an auxiliary armature connected to excite said field winding, a supply-circuit-excited field winding for the exciting armature for producing a predetermined voltage-fluctuation damping effect, a

second field winding of the series type for said exciting armature, and further damping means comprising a variable translating device connected in shunt to said series-type field winding.

20. In a system of direct-current regenerative control, the combination with a supply circuit and a momentum-driven main dynamo-electric machine having an armature and a field winding, of an auxiliary armature connected to excite said field winding, a resistor connected in series-circuit relation with said main armature and in parallel-circuit relation to said main field winding and said exciting armature, and means for varying the excitation of the exciting armature substantially in proportion to the current traversing said armature.

In testimony whereof, I have hereunto subscribed my name this 29th day of April 1916.

RUDOLF E. HELLMUND.
